UNITED STATES PATENT OFFICE.

HAROLD JENNINGS KITCHEN, OF LUTON, ENGLAND.

TLTING FURNACE OR THE LIKE.

1,257,879.

Specification of Letters Patent. Patented Feb. 26, 1918.

Application filed March 7, 1917. Serial No. 153,117.

To all whom it may concern:

Be it known that I, HAROLD JENNINGS KITCHEN, a subject of the King of Great Britain, residing in Luton, England, have invented certain new and useful Improvements in Tilting Furnaces or the like, of which the following is a specification.

The invention relates to tilting furnaces, ladles or other receptacles from which molten metal, slag or the like is poured, and to means for supporting the receptacle in such a manner that, when tilted in order to discharge the contents, the latter pours from the lip or spout in a direction which is practically constant during the discharge and consequently obviates the necessity for any displacement of the vessel which receives the contents.

For this purpose, according to the invention, the furnace bed or other receptacle containing the molten metal is supported on friction rollers engaging with wheels running on suitably disposed rails, the wheels and rollers being so proportioned that as either spout, if there is more than one provided, is moved in one direction by the tilting of the receptacle to which it is attached, it is moved in the opposite direction by the supporting wheels through the same horizontal distance.

In the accompanying drawing, Figure 1 represents in end elevation, and Fig. 2 represents in side elevation, partly in section on the line 2—2, Fig. 1, an example of an arrangement according to the invention as applied to an electric furnace.

Fig. 1^a shows a detail of the tilting gear. The furnace is shown at A; B', B² are the spouts for pouring out the slag and metal respectively. A motor C drives a shaft j (Fig. 1^a) on which is secured a bevel pinion k gearing with a bevel wheel l, the hub of the latter being extended and threaded internally to act as a nut for a screw-threaded rod m which is pivoted at n to the furnace. As the bevel wheel l is prevented from moving axially its rotation causes the rod m and with it the point of attachment to be drawn up or down and to impart the required tilting motion to the furnace. The wheel l is supported on trunnions o¹. Pairs

of friction wheels d', d² secured to axles f', f² of an under frame are rotated, as the furnace is tilted, by rails e', e² attached to the bed of the furnace.

The rotation of the pairs of friction wheels d', d² is imparted by roller sets g', g² secured respectively to the shafts f' and f², to the pairs of wheels h' and h², or to h'¹ and h², according as the direction of rotation of the tilted furnace forces the rollers g' and g² into contact with the wheels h', h² or h'¹, h². The wheels of the frame are coupled by links c', c², c³. The dimensions of the rollers and wheels are such that the horizontal movement of the furnace compensates for the change of position of the spout due to tilting, and the contents are discharged in a constant vertical direction.

Having thus described the nature of the 70 said invention and the best means I know of carrying the same into practical effect, I claim:

1. A receptacle from which molten material can be poured, rails on the receptacle 75 engaging with friction wheels on an under frame, driving wheels on the under frame, the said friction wheels and driving wheels being so proportioned and connected that as the receptacle is tilted in either direction the 80 under frame is moved horizontally, so that the pouring spout of the receptacle remains substantially in a constant vertical plane.

2. A receptacle from which molten material can be poured, an under frame, friction 85 wheels secured to axles mounted in the said under frame, rails attached to the receptacle and engaging with the friction wheels, rollers secured to the said axles in contact with wheels running on suitably disposed rails, 90 the said wheels and rollers being so proportioned that when the receptacle is tilted the spout from which the material is poured remains substantially in a constant vertical plane.

3. A receptacle from which molten material can be poured, a pair of rails in the form of circular arcs secured to the receptacle and resting on two pairs of friction wheels respectively at the fore and aft ends 100 of an under frame, rollers secured to the axles of the friction wheels and resting on

pairs of driving wheels; links connecting the fore and aft driving wheels, and rails on which the driving wheels can run, the said rollers and wheels being so proportioned that when the receptacle is tilted the spout from which the material is poured remains substantially in a constant vertical plane.

In testimony whereof I have signed my name to this specification in the presence of two subscribing witnesses.

HAROLD JENNINGS KITCHEN.
